BUILDING-MOTION FOR SPINNING OR WINDING MACHINES.

1,212,650.

Specification of Letters Patent. Patented Jan. 16, 1917.

Application filed June 28, 1915. Serial No. 35,836.

To all whom it may concern:

Be it known that I, HARRY A. LEONARD, a citizen of the United States, residing at Hopedale, in the county of Worcester and 5 State of Massachusetts, have invented an Improvement in Builder-Motions for Spinning or Winding Machines, of which the following description, in connection with the accompanying drawings, is a specification, like letters on the drawings representing 10 like parts.

The invention to be hereinafter described relates to spinning or winding machines, and more particularly to the builder motions 15 of such machines.

It is customary in looms of the "feeler" type, wherein the filling is to be changed prior to complete exhaustion of that in the running shuttle, to provide certain preliminary windings or a "bunch" of the filling on the carrier or bobbin sufficient in amount 20 to permit the shuttle to lay filling in the shed for one or more picks after the feeler mechanism has indicated approaching exhaustion of the filling to thereby prevent a partial or full failure of the filling to be laid prior to replenishment. In some forms 25 of feeler mechanism, the carrier or bobbin is provided with a longitudinally-extending slot, which, when the filling has reached a predetermined degree of exhaustion, is intended 30 to be uncovered by the filling to permit the entrance of the feeler, which thereupon initiates filling replenishment.

To effectively operate in the manner stated, it is necessary that the slot or opening in the filling carrier be properly exposed for the entrance of the feeler, and that there still remain upon the carrier or 40 bobbin a sufficient filling to insure continuity of filling laid in the shed after the feeler has indicated substantial exhaustion. Economy 45 dictates, however, that the amount of filling remaining on the carrier or bobbin at the time of replenishment shall be as small as is consistent with proper continuity of filling laid in the shed after the call for 50 replenishment. The shape of the wound mass upon the carrier or bobbin should be such that a maximum load may be placed upon the bobbin or carrier.

One of the objects of the present invention, therefore, consists in placing upon a carrier or bobbin of the recessed or slot type,

preliminary windings of filling of sufficient 55 amount beyond one end of the slot to enable the shuttle to lay one or more full picks in the shed after substantial exhaustion of the filling and to cover the slot or recess of the carrier or bobbin by one or more layers of 60 filling in such manner as to insure complete and uninterrupted exposure of the slot or opening to the entrance of the feeler when substantial exhaustion should be indicated.

Another important feature of the invention 65 consists in winding the "bunch" or preliminary windings beyond one end of the slot or recess in the carrier or bobbin with a short traverse, then imparting a long or maximum traverse to the windings to cover 70 the slot or recess, and thereafter building the base of the wound mass with an intermediate and gradually increasing traverse and upon completion thereof to impart a service or regular traverse to the windings. 75 By placing the filling upon the carrier or bobbin in the manner stated, a maximum amount of filling is laid thereon, and when the filling has reached a predetermined degree 80 of exhaustion in the weaving operation, the windings covering the slot or recess are completely withdrawn from the carrier or bobbin to expose the full length of the recess or opening therein to the feeler so that there will be no interference with 85 the feeler action in entering the recess or opening in the carrier or bobbin.

The above and various other features of the present invention will best be made clear from the following description and accompanying drawings of a good practical form of the invention, it being understood that details thereof may be changed or modified within the true scope of the invention, as defined by the claims.

In the drawings:—Figure 1 is a side elevation of sufficient parts of a spinning or winding machine to show the association of the present invention therewith, some of the parts being broken away to show other parts 95 beyond; Fig. 2 is a plan view of the builder motion shown by Fig. 1, some of the parts being in section and others broken away for 100 clearness of illustration; Fig. 3 is an enlarged detail section on the line 3—3, Fig. 105 2; and Fig. 4 shows in somewhat exaggerated form the character of windings constituting the preliminary and the slot cover-

ing layers, and illustrating graphically the relation of the two characters of windings. Fig. 5 is a detail partly in section, showing the gear and rack, the traverse screw and its connection with the swing frame. 5

The machine frame may be of usual or any desired form, and as shown, comprises the side pieces 1 and longitudinal tie beams 2, 3, and 4. In exploitation of the present 10 invention, it is shown as applied to the builder motion of a worsted spinning frame, wherein the carriers or bobbins 5 are mounted upon dead or fixed spindles 6 and rotated by suitable means, such as belts, which 15 engage the pulleys or whirls 7 to which the carriers or bobbins may be suitably connected. In such form of worsted spinning, it is usual to employ caps, such as shown in part at 8, Fig. 1, which are carried upon 20 the fixed or dead spindles 6. While the present invention has special advantages in connection with such form of spinning frame, it is to be understood that it is not restricted thereto, and that the invention in 25 some aspects is applicable to any spinning or winding machine.

The fixed or dead spindles 6 are suitably mounted on the main frame or beam 4 and pass upward therefrom through the "way plate" or traverse rail 9 which carries the 30 bearings for the pulleys or whirls 7. Extending downward from the "way plate" 9 are the rods 10, only one of which is shown, connected at their lower ends to the builder 35 motion, the general construction being such that the builder motion, to be described, imparts the desired up and down or traverse movement to the "way plate" 9 and consequently to the bobbins or carriers connected 40 to the pulleys or whirls 7 to lay the yarn or thread upon the bobbins or carriers in the desired manner.

At its lower end the rod 10 is connected to the arm 11 to which is secured one end of a 45 flexible connection, such as the chain 12, the other end being secured to the traverse rod 13 after passing over suitable guide pulleys 14 and 15 rotatably mounted in the bracket 16 secured to the machine frame. Only one 50 rod 10 is illustrated as connecting the way plate 9 to the traverse rail 13, but in practice there will be several of such rods, depending upon the length of the frame, number of spindles, and the like.

55 Secured to the traverse rail 13 is a lug 17 provided with an adjusting screw 18 adapted to engage an opposed lug 19 on an arm 20 adjustably secured to the rail 13 by suitable means, such as the bolt 21, the construction being such that the arm 20 may be adjusted on the rail 13. The arm 20 has a head 22 which bears against one end of the traverse screw 23. From this construction it will be apparent that any longitudinal 60 movement given the traverse screw 23 will

be transmitted as an up-and-down or traverse movement to the "way plate" 9 and the bobbins or carriers 5.

Depending from the beam 2 is a bracket 24, Fig. 1, to which is pivotally connected 70 at its lower portion, as 26, the swing frame 25 provided at its upper portion with a swiveled and internally threaded block or nut 27 through which passes by threaded engagement, the traverse screw 23. The block 75 27 may be connected to the swing frame in any appropriate manner, but as indicated in Fig. 1, the upper portion of the swing frame 25 is bifurcated and in such bifurcation 80 the block 27 is swiveled, as at 29, the construction being such that the traverse screw 23, may by turning movement, be moved longitudinally with relation to the block 27 and swing frame 25. From this construction, it will be apparent that if the frame 25 be 85 swung about its fulcrum 26, that the traverse screw 23 and the traverse rod 13 will be moved longitudinally and that by turning movement of the traverse screw 23 such longitudinal movement as is imparted by the 90 swing frame 25 will be modified. It will also be apparent that any modification or variation in the swinging movement of the swing frame 25 will be transmitted to the screw and traverse rod. 95

It will be appropriate to describe one form of means for imparting swinging movement to the swing frame and turning movement to the traverse screw, and thereafter the features whereby the actions of these parts are 100 modified to accord with the desired ends to be secured.

Mounted in suitable bearings supported by the machine frame is the cam shaft 30 having mounted thereon the cam 31, Figs. 105 1 and 2. This shaft may be driven from any suitable or convenient source of power to impart rotative movement to the cam 31. Adjustably pivoted upon the machine frame 110 is the swing frame actuator, preferably comprising the arms 32, Figs. 1 and 2, pivotally connected at 33 in the slot 34 of a bracket 35 secured to the frame of the machine. The swing frame actuator preferably has a roller 36 journaled between the arms 32 and adapted 115 to bear upon the cam 31.

At the side opposite the roller 36 the swing frame actuator has a bearing surface 37, Fig. 1, against which rides a roller 38 carried by the swing frame 25. From the construction thus far described, it will be apparent that the cam 31 will impart to the swing frame 25, through the swing frame actuator, and roller carried by the swing frame, a rocking movement about its fulcrum 26, and that such rocking movement of the swinging frame, will impart to the traverse screw and rod, and perforce to the bobbins or carriers on the "way plate", movements longitudinally thereof. It may be 120 125 130

noted that the weight of the "way plate" and bobbins or carriers is transmitted through the plates 10, 11, 12, 13 and 23 to the swing frame 25, and serves to hold the 5 roller 38 against the bearing face 37 of the swing frame actuator.

In order that the swinging movement of the swing frame 25 may lay the yarn or thread upon the bobbins or carriers by traverses gradually progressing toward the top 10 of the bobbins or carriers, means are provided for turning the traverse screw, a good practical form of which comprises a worm 38^x, Fig. 2, on the shaft 30 which meshes 15 with a worm wheel 39 on the shaft 40 mounted in a suitable bearing 41 and carrying a gear 42. The gear 42 is in operative engagement with a gear 44 through the idler gear 43. In order to connect the gear 44 20 with the traverse screw and permit such screw to move longitudinally under control of the swing frame, and also to permit such screw to be turned by hand to reset the parts for commencement of the winding operation, 25 the following means is preferably employed.

The gear 44 is mounted upon and secured to a sleeve 45 which passes through the bearing 46 and has a limited longitudinal movement in said bearing. The sleeve 30 45 where it passes through the bearing 46 is preferably of somewhat smaller diameter, as at 47, than the main portion of the sleeve and is provided with a collar 48. The sleeve 35 45 is provided with a groove 49 adapted to be engaged by an arm 50 pivoted at 51 to the machine frame, whereby the sleeve is held normally in position with the gear 44 operatively engaged with the idler 43. By 40 disengaging the arm 50 from the groove 49, the sleeve 45 may be moved longitudinally to disengage the gears 44 and 43.

Splined to the sleeve 45, as indicated by dotted lines, Fig. 1, and movable longitudinally within said sleeve, is the shaft 51, carrying the gear 52 beyond which extends the traverse screw 23 formed as part of or connected for movement with said shaft. The gear 52 is provided with long and short 50 teeth, as indicated in Fig. 5, and is adapted at times to be engaged with and at other times to be disengaged from the rack 53 to which is connected by suitable means, such as the bolt 56, the traverse slide 54 movable longitudinally of the swing frame 25 in suitable guideway, as 55. The bolt 56 is preferably passed through the lower end portion 57 of the rack and threaded to the shoulder 58 of the traverse slide, but any suitable 60 form of connection may be employed, the essentials in this respect being that the position of the main traverse slide 54 on the swing frame 25 may be controlled by the rack 53 and gear 52, as will more fully appear.

From the construction thus far described, it will be seen that as the actuator 32 is moved by the cam 31, it will act upon the roller 38 which is carried by the traverse slide 54 through the means presently described, to move the swing frame 25 to the right, Fig. 1, against the thrust of the traverse rod, way plate, and connected parts, and that the amount of movement thus imparted to the swing frame and perforce, the 70 "way plate", will depend upon the position of the traverse slide 54 or the roller 38.

As hereinbefore stated, it is desirable in winding filling upon bobbins or other carriers having a feeler slot or opening, to place 80 a few preliminary windings of filling beyond one end of the feeler slot or opening, and then to place a layer of windings over the entire slot or opening, so that as the filling carrier or bobbin is unwound in the 85 loom, the entire slot or opening in the carrier will be opened or uncovered for the entrance of the feeler prior to or just about the time the filling draws from the preliminary windings. This insures unobstructed 90 coöperation between the feeler and the opening or slot in the carrier or bobbin.

The main traverse slide 54 is provided with transverse guideways for a transversely movable slide, which, for identification, may be termed the bunch builder slide. These guideways comprise the laterally-extending portions 59, Fig. 3, in which is mounted the bunch builder slide 60, the upwardly-extending arms of which afford a 95 support for the roller 38. Between the side portions 61 of the bunch builder slide, Fig. 2, extends the rod 62 on which slides the cam follower 63 having portions 64 embracing the cross-piece 64^x of the bunch builder slide, 100 whereby the cam follower 63 is adapted for movements transversely of the slide. The cam follower 63 is provided with an extension 65 adapted at times to engage the grooves of a rotating block or cam 66, and 105 when freed therefrom to be moved to initial position at one side of the bunch builder slide by a suitable spring, such as 67, which may conveniently be mounted upon the rod 62 and bear at one end against a side portion 110 61 of the slide and at the other against a face of the cam follower, substantially as indicated in Fig. 2. The block or cam 66 is provided with the worm-like groove 69, a portion 70 of which is deeper than the remainder, and when the extension 65 of the cam follower is in the more shallow portion 115 of said groove, the bunch builder slide will be forced outward or toward the actuator 32, but when it is engaged with the deeper 120 portion of the groove, the bunch builder slide will be permitted to move in the opposite direction under the weight of the way plate, filling carriers, and connected parts, 125 as will be readily understood.

The block or cam 66 is rotatably mounted on a shaft 72 in bearings 71 carried by the swing frame 25, Fig. 3, said shaft being extended to one side of the swing frame and 5 provided with a sprocket wheel 73, by which said cam 66 is rotated through a sprocket chain 74 and sprocket wheel 75 from the shaft 76, Fig. 2. The shaft 76 may appropriately be the power shaft for the builder 10 motion, and is shown as also provided with the sprocket wheel 77 connected by sprocket chain 78 to the sprocket wheel 79 on the cam shaft 30 by which the latter may be driven preferably at the same speed as the cam 66. 15 At the commencement of the winding operation, the parts are relatively positioned as indicated in Fig. 1, wherein the traverse slide 54 and its connected rack 52 are shown in raised position on the swing frame 25 20 with the rack in engagement with the gear 52 on the shaft 51. Upon actuation of the cam shaft 30, motion is transmitted from the cam 31 through the actuator, the bunch builder slide, and traverse slide to the swing 25 frame 25, the first movement of said parts effecting the traverse of the yarn upon the filling carrier as indicated at *a*, Fig. 4. The next or upward traverse movement will lay 30 the yarn, as indicated at *b*, Fig. 4, the traverse *b* being substantially of the same extent as the traverse *a* and varying therefrom only in a small increment due to the lowering of the traverse slide 54 and the turning movement of the screw 23. An appropriate 35 number of such traverses may be laid upon the filling carrier to provide a suitable supply of filling in the preliminary windings, three of such traverses being indicated in Fig. 4. During this time, that is, during 40 the formation of the preliminary windings *ab*, the traverse slide 54 was in raised position and the cam follower 65 was in engagement with the cam groove in the cam 66, as indicated in Figs. 2 and 3. As hereinbefore 45 indicated, it is desirable that the feeler slot *c* in the bobbin *d* should be covered by one or more layers of filling having a traverse of maximum length and extending from the base portion of the preliminary windings 50 over the entire slot *c* in the bobbin. To effect this maximum traverse, the cam 66 is provided with the deep grooved portion 70 which, as the cam follower 65 moves transversely of the bunch builder slide, under the 55 action of the worm or groove 69, engages the end of the cam follower and the weight of the way plate and the connected parts at once forces the swing frame to the left, thereby dropping the way plate and causing 60 a maximum traverse to lay a layer of filling *e* over the feeler slot *c* of the carrier.

As the cam 66 continues to rotate, the cam follower 65 will gradually ride up the deep portion of the cam groove into the more 65 shallow portion thereof. During this move-

ment of the cam 66 and the cam follower, the traverse slide 54 has been gradually lowered through the gear 52 and rack 53 until upon the completion of the maximum traverse *e*, the end of the follower 65 which was 70 engaged with the cam 66, is lowered out of engagement therewith by the downward movement of the traverse slide 54, whereupon the spring 67 acts upon the follower 65 to return it to initial position. When the 75 cam follower 65 is thus lowered by the slide 54 out of engagement with the cam 66, the rear edge portions 61 of the bunch builder slide 60 engage the longitudinal guideways 80, Figs. 2 and 3, and thereafter transmit 80 the thrust due to the weight of the way plate and connected parts direct to the swing frame 25. As the traverse slide 54 continues to be lowered by means of the rack 85 and gear 52, the base portion of the 85 wound bobbin is formed by the traverse of gradually increasing length, until when the traverse slide 54 has reached its lowest position which may be determined by an adjusting screw 81 threaded into the lower 90 portion 82 of the traverse slide 54, the base portion of the wound bobbin has been completed and the service or regular traverse will then be initiated and maintained throughout the remainder of the winding 95 operation. In order to determine the low position of the traverse slide 54, the swing frame 25 may have a lowered portion 83, Fig. 3, against which the end of the adjusting screw 81 may contact; and when or 100 about the time these parts come into contacting relation, the gear 52 and its connected screw 23 will have been moved to the left, Fig. 1, due to the rotation of the screw in the block 27, so that at such time 105 the rack and gear become disengaged and remain so during the remainder of the winding operation.

The bobbins or filling carriers having now been completely wound, it becomes necessary to reset the parts for another winding operation; and to this end, the arm 50 is thrown out of engagement with the groove 49 of the collar 45, the latter is moved to disengage the gears 44 and 43, and is then 110 turned by the hand wheel 84 to thereby turn back the screw. As the rod 51 and screw 23 are thus turned, the gear 52 will be moved to the right into operative relation with the rack which is now in lowered position, and a short tooth of the gear 52 will move into engagement with the teeth of the rack and thereby raise the same to its upper position. As the rack is thus raised, the traverse slide 54 and with it the bunch 115 builder slide and its follower 65, is brought into engagement with a shallow portion of the groove in the cam 66, substantially as indicated in Fig. 2, whereupon the sleeve 120 45 is returned to normal position, the gears 125 130

44 and 43 operatively engaged, and the parts locked in such engaging relation by the arm 50.

It is sometimes desirable to ease the pressure between the actuator 32 and the bunch builder slide or its roller 38 as the parts are moved or returned to initial position in the manner hereinbefore described; and one appropriate form of means to this end consists of a hand lever 85 which may be appropriately pivoted at 86 to the machine frame and have a cam portion 87 to which may be secured a chain or other flexible connection 88. The flexible connection 88 may 15 appropriately extend over a guide pulley 89 supported on the machine frame as by the bracket 90, and the end of said connection may be secured to the hook 91 swiveled in the upper end of the swing frame 25, the 20 construction being such that upon movement of the handle 85 to the left, Fig. 1, the swing frame 25, screw 23, shaft 51, and connected parts to the way plate 9, may be moved relatively to the actuator 32 so that 25 the upward movement of the traverse slide 54 may be facilitated.

The particulars of the means herein illustrated and described constitute a good, practical and convenient form of the present invention; but it is obvious that changes may be made in the mechanical details without departing from the true scope of the actual invention, as the idea of means such as the traverse slide longitudinally movable of the 30 swing frame and a bunch builder slide transversely movable relatively thereto to effect the formation of the wound filling carriers or bobbins is thought to be broadly new; and this and other features of the invention 35 may be embodied in different form of means.

What is claimed is: —

1. In a machine of the character described, the combination of a builder cam, a traverse member, a movable frame between the 45 builder cam and traverse member, motion transmitting devices between the movable frame and builder cam to transmit motion to the frame from the cam, and means for automatically moving said devices longitudinally and also transversely of the movable frame to effect variable movements to said frame and traverse member.

2. A builder motion for spinning or winding machines, comprising a cam, a traverse member, a movable frame between the cam and traverse member, a traverse slide movable longitudinally of the said frame, a bunch builder slide mounted for movement transversely of said frame, and means for 50 transmitting movement from said cam through the bunch builder slide to the traverse member.

3. A builder motion for spinning or winding machines, comprising a cam, a traverse 55 rod, a swing frame between the cam and

traverse rod, a traverse slide movable longitudinally of the swing frame, a bunch builder slide mounted for movement transversely of said frame, means for transmitting movement from said cam through the bunch builder slide to the traverse rod, and means for effecting movement of the bunch builder slide transversely of the swing frame.

4. In a spinning or winding machine, the combination of a series of spindles for supporting filling carriers to be wound with filling, a traverse rod for effecting relative traverse movement of the filling carriers and filling as the latter is wound thereon, a cam for moving the traverse rod, and means between the cam and traverse rod for modifying the movement transmitted to said rod by the cam, comprising a swing frame, a traverse slide mounted thereon, and a bunch builder slide mounted on the traverse slide.

5. A builder motion for spinning or winding machines, comprising a cam, a traverse rod, a swing frame between the cam and traverse rod, a traverse slide movable longitudinally of the swing frame, a part carried by the traverse slide and through which the motion of the cam is transmitted to the swing frame, means for moving the traverse slide in one direction and said part in another direction to effect a number of movements of minimum traverse to said traverse rod, then a maximum traverse, then a plural number of medium traverses of gradually increasing length and thereafter a series of service traverses of uniform length.

6. A builder motion for spinning or winding machines, comprising a series of spindles for supporting carriers or bobbins to be wound with filling, a cam, means between the cam and spindles for laying the filling on the carriers by a short traverse to form preliminary windings and then a traverse of maximum length, and thereafter by service traverse, comprising a swing frame, a traverse slide movable longitudinally thereof, a member carried by the traverse slide through which motion is transmitted from the cam to the swing frame, and means for causing said member to assume different positions transversely of the traverse slide to vary the movement of the swing frame.

7. A builder motion for spinning or winding machines, comprising a series of spindles for supporting carriers or bobbins to be wound with filling, a cam, means between the cam and spindles for laying the filling on the carriers by a short traverse to form preliminary windings and then a traverse of maximum length, and thereafter by service traverse, comprising a swing frame, a traverse slide movable longitudinally thereof, a member carried by the traverse slide through which motion is transmitted from the cam to the swing frame, and a block

- or cam for controlling the transverse position of said member relative to the swing frame.
8. A builder motion, comprising a cam, a swing frame, a traverse slide movable longitudinally of the swing frame, a slide movable transversely of the traverse slide and adapted to transmit movement from the cam to the swing frame, and means for moving the transversely movable slide transversely of the traverse slide.
9. A builder motion, comprising a cam, a swing frame, a traverse slide movable longitudinally of the swing frame, a slide movable transversely of the traverse slide and adapted to transmit movement from the cam to the swing frame, and a cam device mounted on the swing frame and adapted to act upon the transversely movable slide.
20. 10. A builder motion, comprising a cam, a swing frame, a traverse slide movable longitudinally of the swing frame, a slide movable transversely of the traverse slide and adapted to transmit movement from the cam to the swing frame, a cam on the swing frame, and means between the transversely movable slide and the cam on the swing frame for determining the position of the slide.
30. 11. A builder motion, comprising a cam, a swing frame, a traverse slide mounted on the swing frame, a bunch builder slide movable transversely of the traverse slide, an actuator for transmitting movement from the cam through the transversely movable slide to the swing frame, and means for moving the transversely movable slide to different positions transversely of the traverse slide.
40. 12. A builder motion, comprising a cam, a swing frame carrying a traverse slide and a block or cam having depressions of varying depths, and a bunch builder slide movable transversely of the swing frame in accordance with the depth of said depressions.
13. A builder motion, comprising a cam, a swing frame carrying a traverse slide movable longitudinally thereof, a rotatable block or cam mounted on the swing frame, a bunch builder slide movable transversely of the swing frame and adapted to transmit motion from the cam to the swing frame, and means for rotating said block or cam to vary the position of the bunch builder slide.
50. 14. A builder motion, comprising a cam, a swing frame carrying a traverse slide movable longitudinally thereof, a rotatable block or cam mounted on the swing frame, a bunch builder slide movable transversely of the swing frame and adapted to transmit motion from the cam to the swing frame, a follower between the bunch builder slide and rotatable block or cam, and means for
- rotating said block or cam to vary the position of the bunch builder slide.
15. In a spinning or winding machine, the combination of a series of spindles for holding filling carriers having feeler slots, a traverse member, a cam for moving said member to effect relative traverse of the filling and carriers, and means for modifying the movement imparted to the traverse member by said cam, comprising a swing frame, a slide movable longitudinally and transversely thereof and a block or cam for determining the transverse position of the slide to effect preliminary windings of short traverse and feeler slot protecting winding of maximum traverse.
16. In a spinning or winding machine, the combination of a series of spindles for holding filling carriers having feeler slots, a traverse rod, a cam for moving said rod to effect relative traverse of the filling and carriers, means for modifying the movement imparted to the traverse rod by said cam, comprising a swing frame, a slide movable longitudinally thereof, a second slide movable transversely thereof, a block or cam for determining the transverse position of the second slide to effect preliminary windings of short traverse and feeler slot protecting winding of maximum traverse, and means for controlling the position of the said longitudinally movable slide to thereafter effect windings of different traverse.
17. In a spinning or winding machine, the combination of a series of spindles for holding filling carriers having feeler slots, a traverse rod, a cam for moving said rod to effect relative traverse of the filling and carriers, means for modifying the movement imparted to the traverse rod by said cam, comprising a swing frame, a slide movable longitudinally thereof, a second slide movable transversely thereof, a block or cam for determining the transverse position of the second slide to effect preliminary windings of short traverse and feeler slot protecting winding of maximum traverse, and means for moving the first-named slide longitudinally of the swing frame to effect winding of progressively increasing traverse to form the base of the wound carriers.
18. In a spinning or winding machine, the combination of a series of spindles for holding filling carriers having feeler slots, a traverse rod, a cam for moving said rod to effect relative traverse of the filling and carriers, means for modifying the movement imparted to the traverse rod by said cam, comprising a swing frame, a slide movable longitudinally thereof, a second slide movable transversely thereof, a block or cam for determining the transverse position of the second slide to effect preliminary wind-

ings of short traverse and feeler slot protecting winding of maximum traverse, and means for moving the first named slide longitudinally of the swing frame to a limited 5 extent to effect windings of progressively increasing traverse to form the base of the wound carriers and thereafter a uniform or service traverse.

19. In a spinning or winding machine, the 10 combination of a cam, an actuator operated by said cam, a swing frame, a traverse slide movable longitudinally of the swing frame and carrying an actuator engaging portion, a traverse rod and connected parts exerting 15 thrust upon the swing frame to hold the actuator and said engaging portion in contact, and means for relieving the thrust between such parts when desired.

20. In a builder motion, the combination of 20 a cam and swing frame, a traverse slide movable longitudinally of the swing frame, a bunch builder slide mounted for movement toward and from said cam relative to the swing frame, a cam follower, a block or cam 25 adapted to engage said follower at the commencement of the winding operation and after the preliminary windings have been wound to permit movement of the bunch builder slide transversely of the swing 30 frame to lay windings of maximum traverse, and then to cause movement of the bunch builder slide in the opposite direction to lay windings of shorter traverse.

21. In a machine of the character described, the combination of a series of spindles for supporting filling carriers to be wound with filling, a traverse member for effecting relative traverse of the filling carriers and filling as the latter is wound thereon, a cam for moving the traverse member, means between the cam and traverse member for modifying the movement transmitted to said member by the cam, comprising a 40 movable frame, a slide movable with the frame, and means for automatically moving the slide in directions transversely and longitudinally relative to the frame.

22. In a machine of the character described, the combination of a builder cam, 50 traverse mechanism for relatively moving the filling carriers and filling as the latter is wound thereon, a movable frame connected to the traverse mechanism and actuated by said cam, and means for trans-

mitting motion from the cam to the movable 55 frame, said means including a member mounted on the movable frame for transverse and longitudinal movement relative thereto, and means for automatically effecting such transverse and longitudinal movements of said member relative to the said movable frame.

23. In a machine of the character described, the combination of a builder cam and traverse mechanism, a movable frame 65 connected to the traverse mechanism, a member interposed between the builder cam and movable frame for transmitting motion from said cam to the frame, means for moving said member longitudinally relative to the frame, and means for moving said member transversely relative to the frame for modifying the motion transmitted from the cam to said frame and traverse mechanism. 70

24. In a machine of the character described, the combination of a builder cam and traverse mechanism, a movable frame connected to the traverse mechanism, a member interposed between the builder cam and 80 movable frame for transmitting motion from said cam to the frame, means for moving said member longitudinally relative to the frame, and a cam for moving said member transversely relative to the frame. 85

25. In a machine of the character described, the combination of a builder cam and traverse mechanism, a movable frame for actuating the traverse mechanism, motion transmitting devices between the cam 90 and frame for modifying the movements of the frame, a rack and pinion for moving the said devices longitudinally of the frame, and a cam for moving said devices transversely of the frame. 95

26. In a machine of the character described, the combination of a builder cam and traverse mechanism, a movable frame for transmitting movement from the cam to said traverse mechanism, a slide mounted on 100 the frame for movement in two directions relative to said frame for modifying the movement imparted to the frame by the cam, and separate means for moving the slide in said two directions. 105

In testimony whereof, I have signed my name to this specification.

HARRY A. LEONARD.
